UNITED STATES PATENT OFFICE.

JACOB MERWITZ, OF NORTH TROY, NEW YORK.

WATER-MOTOR.

1,364,202.

Specification of Letters Patent.

Patented Jan. 4, 1921.

Application filed October 3, 1919. Serial No. 323,280.

To all whom it may concern:

Be it known that I, JACOB MERWITZ, a citizen of the United States, residing in North Troy, New York, have invented 5 Water-Motors, of which the following is a specification.

One object of my invention is to provide a simple, compact and substantial form of water motor whose parts shall be so disposed 10 that it shall not be likely to get out of order or require repairs for long periods of time;—the construction and arrangement being such as to allow of a short and direct flow of water from a pressure chamber to 15 the cylinders and from the latter to the exhaust chamber.

I further desire to provide a water motor which shall include a novel arrangement of pressure and exhaust chambers, together 20 with a relatively simple form of valve mechanism for controlling the flow of liquid between said chambers and the cylinder.

These objects and other advantageous ends I attain as hereinafter set forth, reference being had to the accompanying drawings, in which,

Figure 1 is a side elevation of a water motor constructed in accordance with my invention;

Fig. 2 is a horizontal section on the line 2—2, Fig. 1; and

Fig. 3 is an enlarged vertical section on the line 3—3, Fig. 1.

Referring to the above drawings, 1 represents a horizontally elongated hollow base structure divided by a longitudinally extending partition 2 into two chambers 3 and 4 of which the first is supplied through a bottom inlet 6 with water under pressure 35 while the latter is similarly provided with two outlets 5—5 also in its lowest or bottom part, through which the water exhausted 40 from the apparatus may escape.

Mounted on the base structure 1 is a series 45 of vertical cylinders 7 having any desired construction but in the present instance illustrated as made in the form of a single casting. The bottom of each of the cylinders is connected to the pressure chamber 3 through a valve seated opening closed by a 50 downwardly opening valve 8 and each cylinder likewise communicates with the exhaust chamber 4 through a second valve seated opening in which is operative an up-

wardly opening valve 9. Each of the cylinders has operative in it a piston or plunger 10 on the bottom face of which is mounted a cup-shaped body of packing 11, such as leather, in which is mounted a disk or washer 12 engaged by a screw 13 whereby 55 said packing is retained in place with its annular flange extending downwardly in the cylinder below the plunger.

Mounted on the cylinder casting is a series of standards 14 which at their upper 65 ends provide bearings for a main shaft 15 extending at right angles to the center lines of the cylinders and having a crank 16 over each of them connected to the adjacent piston or plunger 10 by a rod 17.

Each of the valves 8 is rigidly attached 70 to a vertically slideable block 18 guided in grooves in the side walls of the pressure chamber 3 and having an opening for the reception of a cam 19 fixed to a shaft 20 extending longitudinally through said chamber and projecting outside of the ends thereof. This shaft is driven through suitable gearing 21 from the main shaft 15 and has fixed 75 to that one of its ends distant from said 80 gearing a pinion 22 meshing with a second pinion 23 fixed on a shaft 24 which extends through the exhaust chamber 4. Both of these shafts are mounted in suitable bearings in the base structure 1 and are preferably 85 provided with stuffing boxes where they pass through the walls of said chamber, in order to prevent leakage of the liquid therein. This second shaft is similarly provided 90 with a number of cams 25 operative respectively within the openings of the slides 26. The latter, as in the case of the slides 18, are guided in vertical grooves formed in the walls of the exhaust chamber and are operatively connected to the exhaust valves 9 95 which are normally held seated by springs 27.

The various cams or eccentrics 19 are so mounted on the shaft 20 as to successively open the valves 8, in each instance when the piston of the adjacent cylinder is at the 100 lower part of its stroke. Likewise the cams 25 are so placed as to successively open the valves 9 and thereby permit the exhaust of water from the cylinders when the pistons or plungers 10 have been moved to the outer 105 or upper ends of their respective cylinders. While the cranks 16 may be arranged in any desired relative positions, I have illus-

trated them as each set 90° in advance of the crank to one side of it and 90° behind the crank on the other side.

With the above described arrangement of 5 parts, some one of the valves 8 is open at any given time so that if water under pressure be admitted to the pressure chamber 3 through the inlet pipe 6, the motor will 10 start, owing to the flow of water from said chamber into at least one of said cylinders and the resulting upward movement of the piston or plunger 10 therein. If the cams or eccentrics on the shafts 20 and 24 be properly timed, the valve 8 of the second cylinder 15 will be opened before the first plunger reaches the top of the cylinder, after which the exhaust valve 9 of said first cylinder will be opened, permitting the escape of the water therein just as the first piston reaches the 20 top or upper end of its stroke. The four pistons in the motor illustrated are thus successively actuated and caused to act upon the main shaft 15 which is thus continuously rotated,—motion being transmitted from it 25 to the gearing 21 through the shaft 20 and thence through the gears 22 and 23 to the second shaft 24.

From the above description it will be noted that I have provided a relatively di-

rect path of flow for the water under pressure as it passes from the inlet pipe 6 through the chamber 3 to the various cylinders 7. Likewise the water exhausted from the cylinders is permitted to flow in short direct lines therefrom through the chamber 35 4 to the waste pipe 5 in the bottom thereof.

I claim:

The combination in a water motor, of a base structure, a longitudinal partition therein dividing the same into a pressure 40 and an exhaust chamber; an intake and an exhaust for said chambers respectively; plunger cylinders mounted on said base and communicating with the chambers through valved openings; oppositely operated valves 45 controlling said openings; reciprocating slides operable in grooves in the chambers, each of said slides being connected with one of said valves; two intergeared shafts longitudinally disposed in said chambers; cams 50 on said shafts adapted to engage the slides and impart movement thereto in predetermined sequence; plungers in the cylinders; a crank shaft actuated by said plungers; and means for driving the cam shafts from said 55 crank shaft.

In witness whereof I affix my signature.
JACOB MERWITZ.
